UNITED STATES PATENT OFFICE

CHARLES F. OSGOOD, OF CLAREMONT, NEW HAMPSHIRE, ASSIGNEE TO SULLIVAN MACHINERY COMPANY, A CORPORATION OF MASSACHUSETTS

MINING APPARATUS

Application filed March 31, 1930, Serial No. 440,310. Renewed June 11, 1931.

This invention relates to mining apparatus and more particularly has reference to improvements in coal mining apparatus of the wheel mounted "universal" type adapted 5 to operate while supported and guided by the mine trackway.

An object of this invention is to provide an improved coal mining apparatus. Another object is to provide an improved coal mining apparatus of the wheel mounted "universal" type having improved adjustable kerf cutting mechanism operative to cut kerfs in parallel planes either horizontally or vertically and in intersecting planes, 10 thereby enabling the apparatus to accommodate itself to practically any cutting conditions encountered. Another object is to provide an improved coal mining apparatus of the wheel mounted type adapted to operate 15 while supported and guided by a mine trackway and having an improved adjustable kerf cutting mechanism whereby a kerf may be cut at or near the level of the mine bottom outside and below the level of the mine trackway. Still another object is to provide in a mining apparatus of the aforesaid 20 character improved adjustable kerf cutting mechanism whereby the cutter bar may be positioned to cut a horizontal kerf at or near the level of the mine bottom outside and below the level of the mine trackway or to cut a vertical kerf at the center of the entry midway between the track rails. Yet another object is to provide in a mining 25 apparatus of the aforesaid character improved adjustable kerf cutting mechanism whereby the kerf cutter may be positioned to cut a horizontal kerf at or near the level of the mine bottom outside of and below the level 30 of the trackway and transversely across the end of the trackway, at or near the level of the mine roof, or to cut a series of vertical kerfs in any desired position between the ribs to suit varying mining conditions. Another object is to provide in a mining machine of the aforesaid character adapted to 35 cut the horizontal kerf at or near the level of the mine bottom outside and below the level of the mine trackway, improved adjustable supporting means for the kerf cut- 40

ter so that the kerf cutter may be positioned to make shear cuts at the center of the entry midway between the track rails or in any desired position between the sides of the entry or to make horizontal cuts in any desired position between the mine bottom and the mine roof. Still another object is to provide in a mining apparatus of the aforesaid character an improved rotatable cutter head and adjusting structure whereby the 55 kerf cutter may be positioned to cut a kerf outside and below the level of the mine trackway or to cut vertical kerfs and including means for adjusting the kerf cutter toward and from or into the axial line of the cutter 60 head. These and other objects and advantages of this invention will, however, hereinafter more fully appear.

In the accompanying drawings there is shown for purposes of illustration one form 70 which the invention may assume in practice.

In these drawings,

Fig. 1 is a side elevational view of an illustrative embodiment of the improved mining apparatus;

Fig. 2 is a plan view of the mining apparatus shown in Fig. 1;

Fig. 3 is an enlarged fragmentary side elevational view of the apparatus shown in Fig. 1, parts being shown in vertical section to 75 illustrate structural details;

Fig. 4 is a sectional view taken substantially on line 4-4 of Fig. 2;

Fig. 5 is a horizontal sectional view taken 80 substantially on line 5-5 of Fig. 1;

Fig. 6 is a transverse vertical sectional view taken substantially on line 6-6 of Fig. 5;

Fig. 7 is a transverse vertical sectional view taken substantially on line 7-7 of 85 Fig. 2;

Fig. 8 is a detail sectional view of a portion of the mechanism shown in Fig. 7;

Fig. 9 is a detail sectional view taken substantially on line 9-9 of Fig. 1, and illustrating a portion of the cutter head structure.

Fig. 10 is a fragmentary bottom view of the cutter supporting structure shown in Fig. 9;

Fig. 17 is a diagrammatic plan view showing the apparatus with the cutter in a position to make a shear cut at the center of the entry.

25 In this illustrative embodiment of the invention there is shown a coal mining apparatus of the wheel mounted "universal" type generally comprising a truck frame 1 supported by wheels 2 adapted to run along a 30 mine trackway 3. Supported in an elevated position on the truck frame is a widely extended horizontal turntable base 4 guiding for rotative movement about a vertical axis, a horizontal turntable 5. Supported by the 35 turntable is a cutter carrying head 6 rotatable about a horizontal axis extending radially from the turntable axis and supporting through a parallel motion link structure generally designated 7, a cutter support 8 on 40 which a usual cutter bar 9 is pivotally mounted. Mounted on the rear end of the truck frame is a motor 10, herein preferably of the reversible electric type, which drives a truck wheel driving mechanism generally designated 45 11 and also through suitable connections the mechanism for rotating the turntable, for rotating the cutter head about its axis, for adjusting the link supporting structure 7, for swinging the cutter bar 9 about 50 its pivot and for actuating the cutting elements on the cutter bar.

Now referring to the specific truck structure, and more particularly the truck wheel driving mechanism 11, it will be noted that 55 the motor shaft 12 is connected by a suitable coupling 13 to a horizontal longitudinally extending power shaft 14 herein arranged midway between the sides of the apparatus. Fixed to the power shaft 14 is a spur pinion 60 15 driving through a spur idler gear 16 a spur gear 17 fixed to a horizontal longitudinally extending shaft 18. The shaft 18 is 65 horizontally disposed and extends longitudinally of the apparatus and is suitably journaled within a base frame 19 rigidly

secured to the sides of the truck frame 1. Fixed to the shaft 18 is a worm 20 (see Fig. 7) meshing with a worm wheel 21 rotatably mounted on a transverse shaft 22 suitably journaled within a base frame 19. This worm 70 wheel 21 may be operatively connected to the shaft 22 by means of a multiple disc clutch 23 of a usual design having suitable cam operating mechanism including a hand lever 24. Fixed to this transverse shaft 22 75 is a brake drum 25 which is engaged by a brake band 26 also arranged to be controlled by the hand lever 24. When this hand lever is moved in one direction the clutch 23 is applied and the brake 26 released and in 80 the opposite direction the brake is applied and the clutch released, although it is obvious that separate operating means may be employed for the clutch and brake if desired. The shaft 22 is connected by a suitable coupling 27 to an aligned shaft 28 likewise suitably journaled within the base frame 19. Journaled on the shaft 28 is a spur gear 29 connectible with the shaft by a jaw clutch 30 splined to the shaft, and this gear meshes 85 with a spur gear 31. Keyed to the shaft 28 is a spur pinion 33 meshing with a spur gear 34 (see also Fig. 8) secured to a transverse shaft 35 arranged parallel with the shaft 28 and likewise suitably journaled within the 90 base frame 19. Splined to the shaft 35 is a 95 slidable pinion 36 adapted to mesh with a spur gear 37 keyed to the hub of the spur gear 29. If desired, suitable operating mechanism may be provided for the clutch 30 and 100 slidable pinion 36 so that when one is connected the other is released. As illustrated, a horizontal transverse shaft 38 is suitably journaled within the base frame 19 and secured to this shaft is a chain sprocket 39 105 connected by a chain and sprocket connection 40 to the rear truck wheel axle. The front and rear truck wheel axles are connected in driving relation by a usual chain and sprocket connection 41. Various means 110 may be employed for effecting rotation of the shaft 38 selectively in opposite directions and in the illustrative form disclosed includes a bevel gear 42 keyed to the hub of the spur gear 31 and meshing with a bevel gear 43 suitably journaled within the frame 19. Meshing with the bevel gear 43 is a bevel gear 44. The bevel gears 42 and 44 115 rotate in opposite directions and a jaw clutch 45 is provided for alternatively connecting these bevel gears to the shaft 38. From the foregoing description it will be evident that when the jaw clutch 30 is shifted to connect the spur gear 29 to the shaft 28 and the pinion 36 is out of mesh with the spur gear 37, the truck wheels may be driven to propel the apparatus in one direction or the other along the mine trackway at a relatively high transport speed from the motor 10 through spur gearing 15, 16, 17, worm gearing 20, 21, fric- 120

tion clutch 23, shafts 22, 28, spur gearing 29, 31, one or the other of the reverse bevels 42, 44 and chain and sprocket connections 40 and 41 connected to the truck wheels 2. It will 5 be also evident that when the jaw clutch 30 is in its released position and the spur pinion 36 is slid into meshing engagement with the gear 37, the truck wheels may be driven to 10 propel the apparatus in one direction or the other along the mine trackway at a relatively slow speed appropriate for cutting through the reduction gearing 33, 34, 36, 37.

Now referring to the improved turntable structure, it will be noted that formed integral with the truck frame is an annulus or ring-like frame portion 47. The turntable 5 is supported by this annular frame and is herein in the form of a circular casting 48 which constitutes the main supporting frame 20 for the kerf cutting mechanism. This casting forms the turntable rotatable about the center of the annular frame 47 and is guided for rotative movement on the annular frame by a depending annular flange 49 fitting 25 the interior periphery of the annular frame and a radial flange 50 overlying the top surface of the annular frame. If desired any suitable anti-friction rollers of any conventional design or any other anti-friction devices 30 may be provided between the turntable and the annular supporting frame 47 for reducing the friction between the turntable and frame. Suitable devices driven by the motor 10 are employed for rotating the turntable relative 35 to the annular supporting frame as herein-after described and in the present instance may include mechanism of the same general character as that described in my co-pending application Ser. No. 432,541, filed 40 March 1, 1930. It will be observed that the horizontal power shaft 14 extends radially toward the center of the turntable and is suitably journaled within the turntable base. Fixed to the forward end of this power shaft 45 is a bevel gear 51 meshing with a bevel gear 52 fixed to a vertical shaft 53 suitably journaled within the turntable casting. Keyed to the vertical shaft 53 intermediate its ends is a spur pinion 54 meshing with a spur gear 55 fixed to a vertical shaft 56 suitably journaled within the turntable casting. The spur gear 55 meshes as shown in Fig. 5 with spur gears 57 and 58. Rotatable with the spur gear 57 is a worm 59 meshing with a 55 slow speed worm wheel 60. This worm wheel is connectible by a usual multiple disc clutch 61 having any suitable type of operating means, to a horizontal shaft 62 suitably journaled within the turntable casting. Fixed to the 60 lower end of this shaft is a worm pinion 66 projecting through an opening 67 in the de-

pending flange 49 and meshing with internal gear teeth 68 herein cut in the inner wall of the annular supporting frame 47. Again referring to Fig. 5 it will be noted that rotatable with the spur gear 58 is a worm 69 meshing with a fast speed worm wheel 70 having its teeth oppositely inclined from the teeth of the worm wheel 60 and operative, upon application of a multiple disc clutch 71, to effect drive of the shaft 62 at a fast 75 speed in a direction opposite from the slow speed drive described above. It will thus be seen that upon the application of one or the other of the friction clutches 61, 71 the turntable 5 may be rotated relative to the annular supporting frame 47 at a relatively high bar positioning speed in one direction or at a relatively slow speed appropriate for cutting in the opposite direction. The worm 80 gearing 63, 64 is herein of the self-locking 85 type and automatically maintains the turntable 5 in its different positions of adjustment relative to the turntable base.

Now referring to the cutting mechanism supported by the turntable 5, it will be observed that the turntable casting is provided with an integral extension frame or arm 73 overlying the annular frame 47 and rigidly braced with respect to the turntable casting by horizontal webs 74. In the present construction, formed integral with this extension frame or arm 73 at its outer end, is a circular frame 75 arranged in a substantially vertical position and rigidly braced with respect to the arm by means of vertical webs 90 95 76. As shown in Fig. 3, secured to this circular frame 75 is an annular retaining and bearing sleeve 77 having an inwardly directed flange 78. Between the flange 78 and a shoulder 79 formed on the circular frame 100 105 75 there is rotatably mounted a sleeve 80 which herein forms a rotatable neck for the cutter head 6 as hereinafter described. This sleeve 80 is fastened to a projecting neck member or frame 81 by which the cutting 110 mechanism is supported as will later be described.

The mechanism for effecting rotation of the cutter head 6 about the neck axis herein comprises a bevel gear 82 fixed to the upper 115 end of the vertical shaft 53 as clearly shown in Fig. 3. Meshing with this bevel gear is a bevel gear 83 fixed to a horizontal shaft 84 extending radially from the axial line of the turntable and suitably journaled within the turntable casting. As illustrated, fixed to this shaft is a spur gear 85 meshing with a spur gear 86 fixed to a parallel shaft 87 likewise suitably journaled within the turntable casting. Secured to this shaft is a 120 bevel pinion 88 meshing with reverse bevels 89 and 90 (see also Fig. 6). These reverse bevels are alternatively connectible by multiple disc clutches 91, 92 respectively of a usual design to a transverse shaft 93 suit- 125 130

ably journaled within the turntable casting. These clutches are provided with any suitable operating means including an operating handle 94 conveniently located at the top 5 of the turntable. Secured to the shaft 93 is a worm 95 meshing with a worm wheel 96 fixed to a horizontal shaft 97 arranged parallel with the shaft 84 above referred to and likewise suitably journaled within the turntable casting. Fixed to the forward end of the shaft 97 is a spur pinion 98 meshing with an internal gear 99 herein formed integral with the sleeve 80 by which the rotatable cutter carrying head 6 is supported. 10 It will thus be seen that upon suitable application of the clutches 91, 92 the cutter head 6 may be rotated about the neck axis in one direction or the other to position the cutter bar 9 into a plurality of intersecting 15 planes about the neck axis. The worm gearing 95, 96 is of the self-locking type and when the clutches 91, 92 are released, automatically locks the cutter head 6 against rotation about the axis of the neck, thereby 20 maintaining the cutter bar in any of its adjusted positions about the neck axis.

The mechanism for supporting the cutter bar 9 on the cutter head 6 and for adjusting the cutter bar into parallel planes toward 25 and from the neck axis and into the axial line of the neck will now be described. As shown in Figs. 9, 10 and 11, the neck frame 30 is provided with parallel side walls 100 extending parallel to and equidistant from the axial line of the neck. Journaled within 35 these side walls is a transverse hinge shaft 101 arranged with its axis perpendicular to and intersecting the axial line of the neck. Journaled on this hinge shaft is a bevel gear 40 102, which meshes with a bevel gear 103 (see also Fig. 4) fixed to the forward end of a neck shaft 104. This neck shaft is suitably journaled within and extends axially through the neck frame 81 and has fixed 45 thereto at its rear end a spur gear 105 meshing with a spur gear 106 fixed to the forward end of a shaft 107 alined with the power shaft 84 above referred to. The shafts 84 and 107 are connected in driving relation by 50 a usual manually controllable jaw clutch 108, this clutch being releasable at will to interrupt the drive for the cutting mechanism. In the present construction, pivotally mounted at its rear end on the hinge shaft 55 101 is a main supporting link member or arm 109 and this link member has pivotal connection at its front end with a transverse shaft 110 connected to the cutter supporting frame 8. A secondary link member or arm 60 111 arranged substantially parallel with the link 109 is pivotally connected at its ends to transverse shafts 112 and 113 respectively connected to the neck frame 81 and cutter supporting frame 8. These arms or links 65 form a parallel motion structure and are so

arranged that, as they are swung about their pivots into different angular positions relative to the neck axis, the cutter bar 9 is maintained at all times parallel to a line parallel with the axial line of the neck, and that by these links the cutter bar may be adjusted into parallel planes toward and from and into the axial line of the neck. The main arm or link 109 has segmental portions 114 overlapping the side walls 100 of the neck frame and these segments have formed thereon worm gear teeth 115. As shown in Fig. 3, meshing with these worm gear segments are parallel worms 116 fixed to parallel shafts 117 suitably journaled within the neck frame 81. The worm gearing 115, 116 is of the self-locking type and automatically maintains the parallel link members in their different positions of adjustment. Fixed to these shafts are worm wheels 118 meshing respectively with worms 119 fixed to a transverse shaft 120 suitably journaled within the neck frame 81. Journaled on the shaft 120 is a spur gear 121 connectible with the shaft by a jaw clutch 122 having suitable operating means including an operating handle 123. This spur gear 121 meshes with an idler gear 124 journaled on a transverse shaft 125 supported within the side walls 100 of the neck frame and this idler gear in turn meshes with a spur gear 126 secured to and rotatable with the bevel gear 102. It will thus be seen that when the spur gear 121 is connected by the clutch 122 to the shaft 120 the arm or link member 109 may be swung about its pivot in one direction or the other by power from the neck shaft 104 through bevel gearing 103, 102, spur gear 126, 124, 121, transverse shaft 120, worm gearing 119, 118, shafts 117, and worms 116 meshing with the worm gear segments 115 secured to the arm.

Now referring to the drive for the cutter chain mounted on the cutter bar 9, it will be noted that meshing with the bevel gear 102 (see Fig. 4) is a bevel gear 127 fixed to the rear end of a shaft 128 suitably rotatably supported by the main arm or link member 109. Fixed to the forward end of this shaft is a bevel gear 129 meshing with a bevel gear 130 journaled on the transverse shaft 110. Meshing with the bevel gear 130 is a bevel gear 131 fixed to a shaft 132 arranged parallel to a line parallel to the neck shaft 104 and suitably journaled within the cutter supporting frame 8. Fixed to the forward end of this shaft is a bevel gear 133 meshing with a bevel gear 134 fixed to a transverse shaft 135 arranged with its axis perpendicular to the axial line of the neck and suitably journaled within the cutter supporting frame. Secured to this shaft 135 is a chain sprocket 136 which engages and drives the usual endless cutter chain 137 mounted for orbital movement on the margin of the cutter bar 9. It will thus be seen that irrespective of 130

the angular position of the parallel link structure relative to the neck frame the cutter chain may be driven, the arrangement of the bevel gearing disclosed permitting pivotal movement of the links about their axes without interrupting the drive. The cutter bar 9 is provided with a plural-part supporting frame structure 138 and the frame sections thereof have annular bearing portions 139 which are rotatably supported on hub portions 140 integral with the cutter supporting frame 8 so that the cutter bar may be swung into different angular positions about the axial line of the shaft 135.

15 The mechanism for swinging the cutter bar 9 about its pivotal axis herein comprises a spur gear 142 meshing with the spur gear 124 above referred to, and rotatably supported on the transverse shaft 112. Formed 20 on the hub of the spur gear 142 is bevel gear 143 meshing with a bevel gear 144 fixed to a shaft 145 suitably journaled on the link 111. Fixed to the forward end of this shaft is a bevel gear 146 meshing with reverse bevels 25 147 and 148 rotatably supported by a transverse shaft 149 journaled on the link 111 and these bevels are alternatively connectible to this shaft by a jaw clutch 150. Fixed to the shaft 149 is a bevel gear 151 meshing with 30 a bevel gear 152 secured to a shaft 153 journaled at the side of the link 111 and driving a worm 154 meshing with a worm wheel 155 fixed to the transverse shaft 113. Secured to the shaft 113 is a worm 156 which meshes 35 with a worm wheel 157 journaled on the hub portion of one of the annular bearing members 139 for the cutter bar 9. Pivotedly mounted at 158 on the cutter bar support is a latch 159 which, when in the position 40 shown in Fig. 4, engages the teeth of the worm wheel 157 to connect rigidly the latter to the cutter bar 9. Any suitable means 160 is employed for holding the latch 159 in its gear engaging position, this means being releasable at will to permit release of the latch 45 from the gear to permit free swinging of the cutter bar about its axis. It will herein be noted that upon connection of one or the other of the reverse bevels 147, 148 to the 50 shaft 149 the cutter bar may be swung in one direction or the other about its pivotal axis relative to the cutter supporting frame 8 and that when the clutch 150 is placed in its neutral position the cutter bar swinging mechanism 55 is entirely disconnected from its drive.

As shown most clearly in Fig. 9, the ends of the shaft 112 which project within the bearing portions at the sides of the link 111 are eccentric relative to the body of the shaft 60 so that by the turning of said shaft, true relation between said link member and the neck structure may be slightly varied for the purpose of correcting any deviation from direct relation between the four bearings of the parallel link structure or for the purpose

of putting said relation out of true sufficient to intentionally slightly tilt the cutter bar out of parallel relation with the axial line of the neck; this being at times desirable when there is a slant in the upper or lower 70 face of the vein of coal or if there is a slight slant in the track on which the apparatus is guided. The adjustment of said shaft 112 is effected manually by a worm wheel 161 fixed to one end of the shaft, and meshing 75 with this worm wheel is a worm 162 fixed to a shaft suitably journaled in a housing 163 secured to the side of the link member 111. The worm shaft is provided with suitable means for the reception of a suitable wrench 80 or other turning instrument. The worm gearing 161, 162 is self-locking and automatically maintains the shaft in its different adjusted positions. It will thus be seen that the cutter bar 9 may be tilted about an 85 axis transverse to the direction of its length as desired.

It will be noted that the motor 10 constitutes the single source of power for driving the various mechanisms of the apparatus and that suitable connections may be provided for supplying electrical energy to this motor and suitable electrical controlling apparatus for controlling such supply if desired, and that a usual power driven cable reel may be 90 mounted on the rear end of the truck and suitably connected to the motor 10 to wind in or pay out the power conductor cable as the apparatus moves along the mine trackway. As such electrical controlling apparatus is 95 usual in coal mining apparatus such as that disclosed, description and illustration of the same is thought unnecessary. It will also be evident that if desired, suitable elevating mechanism may be provided between the 100 turntable base and truck frame so that the turntable may be adjusted into different elevated positions relative to the truck wheels, for instance, power elevating mechanism of 105 the same general character as that disclosed in my copending application Ser. No. 432,541 mentioned above or in my copending application Ser. No. 409,564 filed November 25, 1929.

The preferred mode of operation of the improved mining apparatus will now be described. The apparatus is propelled about the mine forwardly along the mine trackway at a relatively fast transport speed through the truck driving gears 15, 16, 17, 20, 21, 29, 31 driven by the motor 10. When the apparatus 115 is traveling about the mine the turntable 5 is in a position wherein the cutting mechanism extends in a direction substantially lengthwise of the apparatus, as shown in Fig. 2, with the cutter bar elevated to clear the tops of the track rails. When the working face is 120 reached, the fast truck wheel drive is disconnected from the motor 10 by releasing the friction clutch 23 and the jaw clutch 30. If it is desired to make a swinging cut at or near 125 130

the level of the mine bottom in front of the end of the trackway, the operator first manipulates the clutch 150 to connect the bevel gear 147 to the shaft 149 and the cutter bar 9 is 5 swung about its pivot relative to the cutter head from the central position shown in Fig. 2, laterally to a position adjacent the right-hand rib of the entry, the clutch 150 thereafter being disconnected. The operator then 10 shifts the jaw clutch 122 into a position to connect the gear 121 to the shaft 120 and the parallel link members 109, 111 are swung downwardly about their pivots to move the cutter bar 9 from its elevated transport position to a position at or near the level of the mine bottom as shown in Fig. 14, the clutch 122 thereafter being released. The cutter chain drive sprocket 136 is then connected in driving relation with the motor by suitable 15 connection of the clutch 108 and as a result the cutter chain 137 is rapidly circulated about the margin of the cutter bar. The clutch 150 is then connected to effect drive through the bevel gearing 146, 148 and the 20 cutter bar 9 is swung transversely in its plane across the front end of the trackway at a relatively slow cutting speed to make an arcuate cut beneath the coal. When the cutter bar reaches a position adjacent the left-hand 25 rib the clutch 150 is disconnected. After the completion of the swinging cut, the clutch 122 is shifted into its connected position, and upon reversal of the motor 10, the parallel link members 109, 111 are swung upwardly 30 about their pivots to move the cutter bar again into its elevated transport position above the level of the trackway, the clutch 122 thereafter being moved to its released position and the clutch 108 released to disconnect the 35 cutter chain 137 from its drive. With the motor still running in its reverse direction the clutch 30 is connected and upon application of the friction clutch 23 the apparatus is propelled rearwardly at a relatively high speed 40 along the mine trackway to the mine entry. 45

If it is desired to cut a horizontal kerf at or near the level of the mine bottom outside and below the level of the mine trackway, the operator applies the friction clutch 71 thereby 50 causing the turntable 5, together with the cutting mechanism supported thereby, to be swung horizontally from the central position shown in Fig. 2 to the full line position indicated at A in Fig. 15. During horizontal 55 swinging movement of the turntable relative to the truck the cutter bar 9 may be swung simultaneously about its pivot relative to the cutter head in the opposite direction under the control of the clutch 150 until the parts 60 assume the position shown. When the parts are thus disposed with the bar pivot lying outside the mine trackway, the operator releases the friction clutch 71 of the bar swing drive and the clutch 122 is connected thereby 65 causing the parallel link members 109, 111 to be swung downwardly about their pivots until the cutter bar assumes a position at or near the level of the mine bottom, the cutter bar being positioned relative to the mine bottom as shown in Fig. 14 at that time. The clutch 122 is then released. The pinion 36 is then slid into meshing engagement with the gear 37 and upon application of the friction clutch 24, the truck wheels are driven to propel the apparatus bodily in a forward direction along the mine trackway at a relatively slow cutting speed, sumping the cutter bar beneath the coal from position A shown in Fig. 15 to position B indicated in dotted lines in that figure. The friction clutch 23 is then released and the brake 26 set. The operator then applies the friction clutch 61, and the turntable 5 together with the cutter mechanism supported thereby is swung horizontally at a slow cutting speed to effect horizontal swinging movement of the cutter bar in its plane. During the initial swinging movement of the turntable 5 the cutter bar 9 is swung about its pivot under the control of the clutch 150 in a reverse direction until the parts assume a straight line position wherein the cutter bar extends parallel to a line including the bar pivot and the turntable axis as indicated at C in Fig. 15. After the cutter bar has reached the left-hand rib as indicated at D in Fig. 15 and the swinging cut has been completed, the cutter bar 9 is again swung about its pivot rearwardly under the control of the clutch 150 while rotation of the turntable 5 is continued, the turntable and cutter bar swinging simultaneously in opposite directions at that time until they assume the position indicated at E in Fig. 15. The jaw clutch 45 is then shifted to connect the reverse bevel 44 to the shaft 38 and upon application of the friction clutch 23 the apparatus is propelled bodily rearwardly along the mine trackway at a slow cutting speed moving the cutter bar from the position E in Fig. 15 to position F in that figure. After the completion of the cut beneath the coal the parts are again returned to their transport position with the cutter bar disposed in an elevated position above the level of the mine trackway. 111

A horizontal kerf may be cut at or near the level of the mine roof simply by applying one or the other of the friction clutches 91, 92 controlling the reverse bevels 89, 90 respectively, to effect rotation of the cutter head about the neck axis and the clutch 122 is then connected and the parallel link members 109, 111 are swung upwardly about their pivots to move the cutter bar to the position shown at G in Fig. 13, wherein the cutter bar occupies its top cutting position. The cutter bar is then sumped in, swung transversely in its plane, and withdrawn from the coal in accordance with the usual arc wall method of cutting. It will be noted that during any of the horizontal cutting operations described 112

113

above, the cutter bar may be tilted about a transverse axis simply by manually rotating the worm gearing 161, 162 to effect adjustment of the eccentric shaft 112 to vary the 5 relative positions of the link pivots.

A shear or vertical cut may be inserted in the coal face simply by applying one or the other of the reverse frictions 91, 92 controlling the reverse bevels 89, 90 respectively 10 thereby enabling the cutter head to be rotated about the neck axis to bring the cutter bar 9 into a position to swing vertically as shown in Fig. 16. During the shearing operation the cutter bar is first sumped in, then swung 15 downwardly in its plane, and thereafter withdrawn from the coal in a manner similar to that described above in regard to the horizontal cutting in accordance with the arcwall method. It will further be noted that the 20 cutter bar may be moved bodily into parallel planes toward and from the neck axis and into the axial line of the neck thereby enabling the apparatus to cut a series of parallel horizontal kerfs and parallel vertical kerfs and in a plurality of intersecting planes. By adjustment 25 of the parallel link structure supporting the cutter bar, the latter may be moved into a shearing position midway between the sides of the track rails and thereby enable the apparatus to make a center cut, as shown at H in Fig. 17.

As a result of this invention it will be noted that an improved coal mining apparatus is provided having improved adjustable kerf 30 cutting mechanism whereby horizontal kerfs may be cut at or near the level of the mine bottom outside and below the level of the mine trackway and also shear or vertical cuts including a shear or vertical center cut in the 35 coal face midway between the track rails thereby facilitating the shooting of the coal from the solid and increasing the quantity of lump coal obtainable. It will further be noted that under certain conditions the cutter bar may be adjusted to cut at or near the 40 level of the mine roof or if desired, in parallel planes between the mine roof and the mine bottom. It will still further be noted that an improved "universal" coal cutter is 45 provided having improved adjusted kerf cutting mechanism whereby the cutter bar may be positioned to cut in parallel planes either vertically or horizontally in any position between the mine roof and mine bottom and be- 50 tween the ribs of the entry. It will further be noted that an improved coal cutter is provided wherein the adjusting mechanism for the kerf cutting mechanism is extremely flexible, it being possible to operate the apparatus as a mounted bottom cutter, top cutter, center cutter, shear cutter and slabbing machine thereby enabling the apparatus to 55 accommodate itself to practically every mining condition encountered within the normal working range of a track cutting machine.

These and other uses and advantages of the improved mining apparatus will be clearly apparent to those skilled in the art.

While there is in this application specifically described one form which this invention may assume in practice, it will be understood that this form of the same is shown for purposes of illustration and that the invention may be modified and embodied in various other forms without departing 70 from its spirit or the scope of the appended claims. 75

What I claim as new and desire to secure by Letters Patent is:

1. In a mining apparatus, a wheeled truck 80 adapted to run along a mine trackway, and kerf cutting mechanism on said truck including a kerf cutter, adjustable supporting means for said kerf cutter whereby the latter may be positioned wholly outside the trackway and in horizontal planes below the top of the trackway to cut a horizontal kerf at the level of the mine bottom outside and below the level of the mine trackway, or to cut a vertical kerf extending in the direction 90 of the trackway and midway between the sides of the apparatus, and motor operated devices for adjusting said kerf cutter into aforesaid positions. 95

2. In a mining apparatus, a wheeled truck 100 adapted to run along a mine trackway, and kerf cutting mechanism on said truck including a pivoted kerf cutter, adjustable supporting means for said kerf cutter for positioning the latter wholly outside the trackway and in horizontal planes below the top of the trackway to cut a horizontal kerf at the level of the mine bottom outside and below the level of the mine trackway, to cut a vertical kerf extending parallel to the track 105 rails and midway between the track rails, or a horizontal kerf at the level of the mine roof, and motor operated devices for adjusting said kerf cutter into aforesaid positions. 110

3. In a mining apparatus, a wheeled truck 115 adapted to run along a mine trackway, a horizontal turntable on said truck, and kerf cutting mechanism supported by said turntable including a cutter head rotatable about an axis extending radially from the axial line of said turntable, a pivoted kerf cutter supported on said head, and adjustable supporting means for said kerf cutter for moving the latter, while the same remains at all times parallel to said axial line, toward and from the axial line of said head and into said axial line. 120

4. In a mining apparatus, a wheeled truck 125 adapted to run along a mine trackway, a horizontal turntable on said truck, and kerf cutting mechanism supported by said turntable including a rotatable neck frame disposed on a horizontal axis and a pivoted kerf cutter supported by said neck frame and adjustable, while said kerf cutter re- 130

mains at all times parallel to said horizontal axis, into positions toward and from the axial line of said neck frame and into said axial line.

5. In a mining apparatus, a wheeled truck adapted to run along a mine trackway, a horizontal turntable on said truck, motor operated devices for rotating said turntable, a cutter head mounted on said turntable for 10 rotation about an axis extending radially from the axial line of the turntable, motor operated devices for rotating said cutter head about its axis, and a pivoted cutter bar supported by said head and adjustable, 15 while said bar remains at all times parallel to said head axis, relative to said head toward and from the axial line of said head and into said axial line.

6. In a mining apparatus, a wheeled truck 20 adapted to run along a mine trackway, kerf cutting mechanism supported by said truck including a pivoted kerf cutter and adjustable supporting means for said kerf cutter for positioning the latter wholly outside the 25 trackway and in horizontal planes below the top of the trackway to make a horizontal cut at the level of the mine bottom outside and below the level of the mine trackway, or to 30 make a vertical cut extending in the direction of the trackway and midway between the sides of the apparatus, and motor operated devices for adjusting said kerf cutter into aforesaid positions.

7. In a mining apparatus, a wheeled truck 35 adapted to run along a mine trackway, kerf cutting mechanism supported by said truck including a pivoted kerf cutter and adjustable supporting means for said kerf cutter for positioning the latter wholly outside 40 the trackway and in horizontal planes below the top of the trackway to make a horizontal cut at the level of the mine bottom outside and below the level of the mine trackway, or to 45 make a vertical cut extending in the direction of the trackway and midway between the sides of the apparatus, motor operated devices for adjusting said kerf cutter into aforesaid positions, and motor operated devices for driving the truck wheels to propel 50 the apparatus along the mine trackway to effect sumping and withdrawal movements of said kerf cutter.

8. In a mining apparatus, a wheeled truck adapted to run along a mine trackway, kerf 55 cutting mechanism supported by said truck including a pivoted kerf cutter and adjustable supporting means for said kerf cutter for positioning the latter wholly outside the trackway and in horizontal planes below the 60 top of the trackway to make a horizontal cut at the level of the mine bottom outside and below the level of the mine trackway, or to make a vertical cut extending in the direction of the trackway and midway between the 65 sides of the apparatus, motor operated devices

for adjusting said kerf cutter into aforesaid positions, motor operated devices for swinging said kerf cutter about its pivot, and motor operated devices for driving the truck wheels to propel the apparatus along the 70 mine trackway to effect sumping and withdrawal movements of said kerf cutter.

9. In a mining apparatus, a wheeled truck adapted to run along a mine trackway, a horizontal turntable on said truck, a rotatable neck frame mounted on said turntable for rotation about a horizontal axis, a pivoted kerf cutter mounted on said neck frame, adjustable supporting means between said kerf cutter and said neck frame for positioning said kerf cutter in different parallel planes respectively differently spaced from and including the axial line of said neck frame, and motor operated devices for adjusting said kerf cutter into aforesaid positions. 80

10. In a mining apparatus, a wheeled truck adapted to run along a mine trackway, a motor on said truck, devices driven by said motor for driving the truck wheels to propel the apparatus, kerf cutting mechanism supported on said truck including a pivoted kerf cutter and adjustable supporting means for said kerf cutter for positioning the latter at the level of the mine bottom wholly outside of and below the level of the mine trackway 90 or to make a vertical cut extending in the direction of the trackway and midway between the sides of the apparatus, devices driven by said motor for adjusting said kerf cutter into aforesaid positions, and devices driven by said motor for actuating said kerf cutter and for swinging said kerf cutter about its pivot. 95

11. In a mining apparatus, a wheeled truck adapted to run along a mine trackway, a motor carried by said truck, devices driven by said motor for driving the truck wheels to propel the apparatus, a horizontal turntable on said truck, a neck frame mounted on said turntable for rotation about a horizontal axis, 100 a pivoted kerf cutter adjustably mounted on said neck frame for movement, through a series of parallel positions, toward and from and into the axial line of the neck, devices driven by said motor for rotating said turntable, devices driven by said motor for rotating said neck frame about its axis, devices driven by said motor for adjusting said kerf cutter into aforesaid positions, for actuating said kerf cutter and for swinging said kerf cutter about its pivot. 110

12. In a mining apparatus, a wheeled truck adapted to run along a mine trackway, a frame mounted on said truck for rotation about a vertical axis, a rotary supporting body mounted on said frame for rotation about a horizontal axis, an elongated kerf cutter, means intervening said supporting body and said kerf cutter for carrying the latter for orbital movement around the axial 125 130

line of said rotary supporting body and toward and from and into said axial line and to swing in planes parallel to said axial line.

13. In a mining apparatus, a wheeled truck adapted to run along a mine trackway, a frame mounted on said truck for rotation about a vertical axis, a rotary supporting body mounted on said frame for rotation about a horizontal axis, an elongated kerf cutter, means intervening said supporting body and said kerf cutter for carrying the latter in planes parallel to the axial line of said supporting body, for orbital movement around said axial line, and from and toward and into said axial line, and means for actuating said kerf cutter for cutting.

14. In a mining apparatus, a wheeled truck adapted to run along a mine trackway, a frame mounted thereon for rotation about a vertical axis, a rotary body mounted on said frame for rotation about a horizontal axis, an elongated kerf cutter, and means intervening said body and said kerf cutter for carrying the kerf cutter parallel to the axial line of said body, for orbital movement around said line and from and toward and into said line and for swinging said kerf cutter into a plane parallel to said axial line.

15. In a mining apparatus, a wheeled truck adapted to run along a mine trackway, a horizontal turntable on said truck, supporting means having a neck seated rotatably in a bearing on said turntable, an elongated cutting mechanism hinged to said supporting means to permit movement of said mechanism toward and from the axial line of said neck while said cutting mechanism remains parallel to said axial line, and transmission means extending through said neck for actuating said cutting mechanism.

16. In a mining apparatus, a wheeled truck adapted to run along a mine trackway, a support mounted on said truck for adjustment horizontally relative thereto about a vertical axis and including supporting means having a neck seated rotatably in a bearing, an elongated kerf cutting mechanism hinged to said supporting means to permit movement of said mechanism toward and from the axial line of said neck while said cutting mechanism remains parallel to said axial line, and a neck shaft extending through said neck and arranged in operative relation with the cutting mechanism for actuating said cutting mechanism.

17. In a mining apparatus, a wheeled truck adapted to run along a mine trackway, a horizontal turntable on said truck, a kerf cutter, a group of members supporting said kerf cutter and mounted on said turntable, said group being supported for rotation on the turntable on a horizontal axial line and said group being foldable on three lines which are between said kerf cutter and the attachment to the turntable, two of said

lines being transverse to said axial line and the other of said hinge lines being transverse to said two hinge lines last mentioned and perpendicular to said axial line whereby, by the folding and unfolding of said members on the first two hinge lines said kerf cutter is carried bodily by a parallel movement toward and from said axial line and whereby, by the folding and unfolding of said members on the third of said hinge lines the kerf cutter is swung in a plane which is parallel to said axial line, operator controlled means carried by said group to effect folding on said two hinge lines, and operator controlled means to effect folding on said third hinge line, and means for actuating said kerf cutter.

18. In a mining apparatus, a wheeled truck adapted to run along a mine trackway, a rotatable neck frame which is in a bearing which is horizontal, operator controlled power driven means for rotating said neck frame, a kerf cutter, link members supporting said kerf cutter on said neck frame for movement on said neck frame toward and from the axial line of said neck, means extending through said neck frame for actuating said kerf cutter, and means for adjusting said kerf cutter, bodily horizontally to position the same wholly outside the trackway to cut a horizontal kerf at the level of the mine bottom outside and below the level of the mine trackway.

19. In a mining apparatus, a wheeled truck adapted to run along a mine trackway, kerf cutting mechanism mounted thereon including a neck frame rotatable about a horizontal axis and a pivoted kerf cutter adjustably mounted on said neck frame for movement, through a series of parallel positions, toward and from and into the axial line of said neck, mechanism for rotating said neck frame to move said kerf cutter orbitally about the neck axis, and mechanism for adjusting said kerf cutting mechanism bodily horizontally relative to said truck to position said kerf cutter wholly outside the trackway to cut a horizontal kerf at the level of the mine bottom outside and below the level of the mine trackway.

20. In a mining apparatus, a wheeled truck adapted to run along a mine trackway, kerf cutting mechanism mounted thereon including a neck frame rotatable about a horizontal axis and a pivoted kerf cutter adjustably mounted on said neck frame for movement, through a series of parallel positions, toward and from and into the axial line of said neck, mechanism for rotating said neck frame to move said kerf cutter orbitally about the neck axis, and mechanism including a frame mounted on said truck for rotation about a vertical axis, for adjusting said kerf cutting mechanism horizontally relative to said truck to position said kerf cutter to cut

a kerf at the level of the mine bottom outside and below the level of the mine trackway.

21. In a mining apparatus, a wheeled truck adapted to run along a mine trackway, a motor on said truck fixed with respect thereto as to movement about a vertical axis, and kerf cutting mechanism on said truck and driven by said motor including a pivoted kerf cutter and adjustable supporting means for said kerf cutter whereby the latter may be positioned wholly outside the trackway to cut a horizontal kerf at the level of the mine bottom outside and below the level of the mine trackway, or to cut a vertical kerf midway between the sides of the apparatus.

22. In a mining apparatus, a wheeled truck adapted to run along a mine trackway, a motor on said truck fixed with respect thereto as to movement about a vertical axis, and kerf cutting mechanism on said truck and driven by said motor including a kerf cutter, adjustable supporting means for said kerf cutter whereby the latter may be positioned wholly outside the trackway to cut a horizontal kerf at the level of the mine bottom outside and below the level of the mine trackway, or to cut a vertical kerf midway between the sides of the apparatus, and motor operated devices for adjusting said kerf cutter into aforesaid positions.

23. In a mining apparatus, a wheeled truck adapted to run along a mine trackway, a motor on said truck fixed with respect thereto as to movement about a vertical axis, and kerf cutting mechanism on said truck and driven by said motor including a pivoted kerf cutter and adjustable supporting means for said kerf cutter for positioning the latter wholly outside the trackway to cut a horizontal kerf at the level of the mine bottom outside and below the level of the mine trackway, to cut a vertical kerf midway between the track rails, or to cut a horizontal kerf at the level of the mine roof.

24. In a mining apparatus, a wheeled truck adapted to run along a mine trackway, a motor on said truck fixed with respect thereto as to movement about a vertical axis, and kerf cutting mechanism on said truck and driven by said motor including a pivoted kerf cutter, adjustable supporting means for said kerf cutter for positioning the latter wholly outside the trackway to cut a horizontal kerf at the level of the mine bottom outside and below the level of the mine trackway, to cut a vertical kerf midway between the track rails, or to cut a horizontal kerf at the level of the mine roof, and motor operated devices for adjusting said kerf cutter into aforesaid positions.

25. In a mining apparatus, a wheeled truck adapted to run along a mine trackway, a motor on said track fixed with respect thereto as to movement above a vertical axis, and

kerf cutting mechanism on said truck and driven by said motor including a pivoted kerf cutter, and adjustable supporting means for said kerf cutter for positioning the latter into different parallel horizontal planes between the mine bottom and mine roof and in vertical cutting positions between the ribs of the entry, and including means for positioning the cutter bar wholly outside the trackway to cut a horizontal kerf at the level of the mine bottom outside and below the level of the mine trackway.

26. In a mining apparatus, a wheeled truck adapted to run along a mine trackway, a horizontal turntable on said truck, a motor on said truck fixed with respect thereto as to movement about a vertical axis, and kerf cutting mechanism supported by said turntable and driven by said motor including a cutter head rotatable about an axis extending radially from the axial line of said turntable, a pivoted kerf cutter supported on said head, and adjustable supporting means for said kerf cutter for moving the latter bodily toward and from the axial line of said head and into said axial line.

27. In a mining apparatus, a wheeled truck adapted to run along a mine trackway, a horizontal turntable on said truck, a motor on said truck fixed with respect thereto as to movement about a vertical axis, and kerf cutting mechanism supported by said turntable and driven by said motor including a rotatable neck frame disposed on a horizontal axis and a pivoted kerf cutter supported by said neck frame and adjustable bodily toward and from the axial line of said neck frame and into said axial line.

28. In a mining apparatus, a wheeled truck adapted to run along a mine trackway, a horizontal turntable on said truck, a motor on said truck fixed with respect thereto as to movement about a vertical axis, motor operated devices for rotating said turntable, a cutter head mounted on said turntable for rotation about an axis extending radially from the axial line of the turntable, motor operated devices for rotating said cutter head about its axis, and a pivoted cutter bar supported by said head and adjustable bodily relative thereto toward and from the axial line of said head and into said axial line.

29. In a mining apparatus, a wheeled truck adapted to run along a mine trackway, a motor on said truck fixed with respect thereto as to movement about a vertical axis, kerf cutting mechanism supported by said truck and driven by said motor including a pivoted kerf cutter, adjustable supporting means for said kerf cutter for positioning the latter wholly outside the trackway to make a horizontal cut at the level of the mine bottom outside and below the level of the mine trackway, or to make a vertical cut midway between the sides of the apparatus, and motor

operated devices for adjusting said kerf cutter into aforesaid positions.

30. In a mining apparatus, a wheeled truck adapted to run along a mine trackway, a motor on said truck fixed with respect thereto as to movement about a vertical axis, kerf cutting mechanism supported by said truck and driven by said motor including a pivoted kerf cutter, adjustable supporting means for said kerf cutter for positioning the latter wholly outside the trackway to make a horizontal cut at the level of the mine bottom outside and below the level of the mine trackway, or to make a vertical cut midway between the sides of the apparatus, motor operated devices for adjusting said kerf cutter into aforesaid positions, and motor operated devices for driving the truck wheels to propel the apparatus along the mine trackway to effect sumping and withdrawal movements of said kerf cutter.

31. In a mining apparatus, a wheeled truck adapted to run along a mine trackway, a motor on said truck fixed with respect thereto as to movement about a vertical axis, kerf cutting mechanism supported by said truck and driven by said motor including a pivoted kerf cutter, adjustable supporting means for said kerf cutter for positioning the latter wholly outside the trackway to make a horizontal cut at the level of the mine bottom outside and below the level of the mine trackway, or to make a vertical cut midway between the sides of the apparatus, motor operated devices for adjusting said kerf cutter into aforesaid positions, motor operated devices for swinging said kerf cutter about its pivot, and motor operated devices for driving the truck wheels to propel the apparatus along the mine trackway to effect sumping and withdrawal movements of said kerf cutter.

32. In a mining apparatus, a wheeled truck adapted to run along a mine trackway, a motor on said truck fixed with respect thereto as to movement about a vertical axis, a horizontal turntable on said truck, a rotatable neck frame mounted on said turntable for rotation about a horizontal axis, cutting mechanism driven by said motor including a pivoted kerf cutter mounted on said neck frame, adjustable supporting means between said kerf cutter and said neck frame for positioning said kerf cutter in different parallel planes respectively differently spaced from and in the axial line of said neck frame, and motor operated devices for adjusting said kerf cutter into aforesaid positions.

33. In a mining apparatus, a wheeled truck adapted to run along a mine trackway, a motor on said truck, devices driven by said motor for driving the truck wheels to propel the apparatus, kerf cutting mechanism supported on said truck including a pivoted kerf cutter and adjustable supporting means for

said kerf cutter for positioning the latter at the level of the mine bottom wholly outside of and below the level of the mine trackway, or to make a vertical cut midway between the sides of the apparatus, devices driven by said motor for adjusting said kerf cutter into aforesaid positions while said motor remains stationary with respect to said truck, and devices driven by said motor for actuating said kerf cutter and for swinging said kerf cutter about its pivot.

34. In a mining apparatus, a wheeled truck adapted to run along a mine trackway, a motor carried by said truck, devices driven by said motor for driving the truck wheels to propel the apparatus, a horizontal turntable on said truck, a neck frame mounted on said turntable for rotation about a horizontal axis, a pivoted kerf cutter adjustably mounted on said neck frame for movement, through a series of positions in parallel planes, toward and from and into the axial line of the neck, devices driven by said motor for rotating said turntable while said motor remains stationary relative to said truck, devices driven by said motor for rotating said neck frame about its axis, devices driven by said motor for adjusting said kerf cutter into aforesaid positions, for actuating said kerf cutter and for swinging said kerf cutter about its pivot.

35. In a mining apparatus, a wheeled truck adapted to run along a mine trackway, a motor on said truck fixed with respect thereto as to movement about a vertical axis, a frame mounted on said truck for rotation about a vertical axis, a rotary supporting body mounted on said frame for rotation about a horizontal axis, cutting mechanism driven by said motor including an elongated kerf cutter, means intervening said supporting body and said kerf cutter for carrying the latter for orbital movement around the axial line of said rotary supporting body and toward and from and into said axial line and to swing in planes parallel to said axial line.

36. In a mining apparatus, a wheeled truck adapted to run along a mine trackway, a motor on said truck fixed with respect thereto as to movement about a vertical axis, a frame mounted on said truck for rotation about a vertical axis, a rotary supporting body mounted on said frame for rotation about a horizontal axis, cutting mechanism driven by said motor including an elongated kerf cutter, means intervening said supporting body and said kerf cutter for carrying the latter in planes parallel to the axial line of said supporting body, for orbital movement around said axial line, and from and toward and into said axial line, and means for actuating said kerf cutter for cutting.

37. In mining apparatus, a wheeled truck adapted to run along a mine trackway, a motor on said truck fixed with respect thereto

- as to movement about a vertical axis, a frame mounted thereon for rotation about a vertical axis, a rotary body mounted on said frame for rotation about a horizontal axis, cutting mechanism driven by said motor including an elongated kerf cutter, and means intervening said body and said kerf cutter for carrying the kerf cutter parallel to the axial line of said body, for orbital movement 5 around said line and from and toward and into said line and for swinging said kerf cutter in a plane parallel to said axial line.
38. In a mining apparatus, a wheeled truck adapted to run along a mine trackway, a motor on said truck fixed with respect thereto as to movement about a vertical axis, a horizontal turntable on said truck, supporting means having a neck seated rotatably in a bearing on said turntable, cutting mechanism 10 driven by said motor including an elongated cutting mechanism hinged to said supporting means to permit movement of said mechanism toward and from the axial line of said neck while remaining parallel to said axial line, and transmission means extending 15 through said neck for actuating said cutting mechanism.
39. In a mining apparatus, a wheeled truck adapted to run along a mine trackway, a motor on said truck fixed with respect thereto as to movement about a vertical axis, a support mounted on said truck for adjustment horizontally relative thereto about a vertical axis and including supporting means having 20 a neck seated rotatably in a bearing, cutting mechanism driven by said motor including an elongated kerf cutting mechanism hinged to said supporting means to permit movement of said mechanism toward and 25 from the axial line of said neck while remaining parallel to said axial line, and a neck shaft extending through said neck and arranged in operative relation with the cutting mechanism for actuating said cutting mechanism.
40. In a mining apparatus, a wheeled truck adapted to run along a mine trackway, a motor on said truck fixed with respect thereto as to movement about a vertical axis, a horizontal turntable on said truck, a rotary neck 30 resting in a bearing on said turntable, a rotary neck shaft located in said neck on the axis of the latter, cutting mechanism driven by said motor and plurally articulated to said neck and arranged in operative relation to said neck shaft, and operator controlled means for rotating said neck shaft.
41. In a mining apparatus, a wheeled truck adapted to run along a mine trackway, a motor on said truck fixed with respect thereto as to movement about a vertical axis, a horizontal turntable on said truck, a kerf cutter, a group of members supporting said kerf cutter and mounted on said turntable, said group 45 being supported for rotation on the turntable on a horizontal axial line and said group being foldable on three lines which are between said kerf cutter and the attachment to the turntable, two of said lines being transverse to said axial line and the other of said hinge lines being transverse to said two hinge lines last mentioned and perpendicular to said axial line whereby, by the folding and unfolding of said members on the first two hinge lines said kerf cutter is carried bodily by a parallel movement toward and from said axial line and whereby, by the folding and unfolding of said members on the third of said hinge lines the kerf cutter is swung in a plane which is parallel to said axial line, operator controlled means carried by said group to effect folding on said two hinge lines, and operator controlled means to effect folding on said third hinge line, and means driven by 50 said motor for actuating said kerf cutter.
42. In a mining apparatus, a wheeled truck adapted to run along a mine trackway, a motor on said truck fixed with respect thereto as to movement about a vertical axis, a rotatable neck frame which is in a bearing which is horizontal, operator controlled power driven means for rotating said neck frame, a kerf cutter, link members supporting said kerf cutter on said neck frame for movement on said neck frame toward and from the axial line of said neck, means driven by said motor and extending through said neck frame for actuating said kerf cutter, and means for adjusting said kerf cutter bodily horizontally to a position wholly outside the trackway to cut a horizontal kerf at the level of the mine bottom outside and below the level of the mine trackway.
43. In a mining apparatus, a wheeled truck adapted to run along a mine trackway, a motor on said truck fixed with respect thereto as to movement about a vertical axis, kerf cutting mechanism mounted on said truck and driven by said motor, said cutting mechanism including a neck frame rotatable about a horizontal axis and a pivoted kerf cutter adjustably mounted on said neck frame for movement, through a series of positions in parallel planes, toward and from and into the axial line of said neck, mechanism for rotating said neck frame to move said kerf cutter orbitally about the neck axis, and mechanism for adjusting said kerf cutting mechanism bodily horizontally relative to said truck to position said kerf cutter wholly outside the trackway to cut a horizontal kerf at the level of the mine bottom outside and below the level of the mine trackway.
44. In a mining apparatus, a wheeled truck adapted to run along a mine trackway, a motor on said truck fixed with respect thereto as to movement about a vertical axis, kerf cutting mechanism mounted on said truck and driven by said motor, said cutting mechanism including a neck frame rotatable about a horizontal axis and a pivoted kerf cutter adjustably mounted on said neck frame for movement, through a series of positions in parallel planes, toward and from and into the axial line of said neck, mechanism for rotating said neck frame to move said kerf cutter orbitally about the neck axis, and mechanism for adjusting said kerf cutting mechanism bodily horizontally relative to said truck to position said kerf cutter wholly outside the trackway to cut a horizontal kerf at the level of the mine bottom outside and below the level of the mine trackway.

- zontal axis and a pivoted kerf cutter adjustably mounted on said neck frame for movement, through a series of positions in parallel planes, toward and from and into the axial line of said neck, mechanism for rotating said neck frame to move said kerf cutter orbitally about the neck axis, and mechanism including a frame mounted on said truck for rotation about a vertical axis, for adjusting 5 said kerf cutting mechanism bodily horizontally relative to said truck to position said kerf cutter to cut a kerf at the level of the mine bottom outside and below the level of the mine trackway.
- 10 45. In a mining apparatus, a wheeled truck adapted to run along a mine trackway, a motor on said truck, a horizontal turntable on said truck and turnable relative to said motor and truck about a vertical axis, and kerf cutting mechanism supported by said turntable including a support rotatable about an axis extending radially from the axial line of said turntable, a pivoted kerf cutter carried by said support and swingable relative 20 thereto, adjustable supporting means for said kerf cutter for moving said kerf cutter, while the latter remains at all times parallel to the axial line of the support, toward and from the axial line of said support, and devices 25 driven by said motor for actuating said adjustable supporting means to move said kerf cutter into aforesaid positions.
46. In a mining apparatus, a wheeled truck adapted to run along a mine trackway, a 30 motor on said truck, a horizontal turntable on said truck and turnable relative to said motor and truck about a vertical axis, kerf cutting mechanism supported by said turntable including a support rotatable about an axis extending radially from the axial line of 35 said turntable, a pivoted kerf cutter carried by said support and swingable relative thereto, said kerf cutter having cutting appliances thereon, adjustable supporting means for said 40 kerf cutter for moving said kerf cutter toward and from the axial line of said support, and devices driven by said motor for actuating the cutting appliances on said kerf cutter.
- 45 47. In a mining apparatus, a wheeled truck adapted to travel along a mine trackway, and adjustable kerf cutting mechanism on said truck including a kerf cutter, and an adjustable supporting structure between said kerf cutter and said truck including a support turnable horizontally relative to said truck, a second support mounted on said first support for rotation relative thereto about a 50 horizontal axis, and devices for adjusting said supporting structure to position said kerf cutter to cut a horizontal kerf at the level of the mine floor outside and below the level of the mine trackway and to cut a vertical kerf 55 in a plane in which said second support axis lies when said second support is in a position extending longitudinally of the truck.
- 55 48. In a mining apparatus, a wheeled truck adapted to travel along a mine trackway, a horizontal turntable on said truck, and adjustable kerf cutting mechanism on said turntable including a kerf cutter and adjustable supporting structure between said kerf cutter and said turntable including a support rotatable relative to said turntable about an axis 60 extending radially from the axial line of said turntable, and devices for adjusting said supporting structure to position said kerf cutter to cut a horizontal kerf at the level of the mine floor outside of and below the level of the mine trackway, and to cut a vertical kerf in a plane in which said support axis lies when said support is in a position extending longitudinally of the truck.
- 65 49. In a mining apparatus, a wheeled truck adapted to travel along a mine trackway, and kerf cutting mechanism including a pivoted kerf cutter and an adjustable supporting structure for said kerf cutter including means swingable horizontally relative to said truck to position said kerf cutter wholly outside the trackway to cut a kerf at the level of the mine floor outside and below the level of the mine trackway and movable to adjust said kerf cutter into different horizontal planes 70 relative to the truck, and swingable about a longitudinal axis relative to said truck to position said kerf cutter to make a vertical shearing cut in a plane in which said longitudinal axis lies when said supporting structure is in a position extending longitudinally and midway between the sides of the truck and also adjustable to position said kerf cutter in different parallel planes when in such 75 vertical shearing position.
- 75 50. In a mining apparatus, a wheeled truck adapted to run along a mine trackway, a motor on said truck fixed with respect thereto as to movement about a vertical axis, kerf cutting mechanism on said truck and driven by said motor including a pivoted kerf cutter and adjustable supporting means for said kerf cutter whereby the latter may be positioned wholly outside the trackway to cut a 80 horizontal kerf at the level of the mine bottom outside and below the level of the mine trackway, or positioned to cut a vertical kerf midway between the sides of the apparatus, and motor operated devices for driving the truck wheels to propel the apparatus bodily 85 along the mine trackway to effect sumping and withdrawal movements of said kerf cutter.
- 85 51. In a mining apparatus, a wheeled truck adapted to run along a mine trackway, a motor on said truck fixed with respect thereto as to movement about a vertical axis, kerf cutting mechanism on said truck and driven by said motor including a kerf cutter, adjustable supporting means for said 90

kerf cutter whereby the latter may be positioned wholly outside the trackway to cut a horizontal kerf at the level of the mine bottom outside and below the level of the mine trackway, or positioned to cut a vertical kerf midway between the sides of the apparatus, motor operated devices for adjusting said kerf cutter into aforesaid positions, and motor operated devices for driving the truck wheels to propel the apparatus bodily along the mine trackway to effect sumping and withdrawal movements of said kerf cutter.

52. In a mining apparatus, a wheeled truck adapted to run along a mine trackway, a motor on said truck fixed with respect thereto as to movement about a vertical axis, kerf cutting mechanism on said truck and driven by said motor including a pivoted kerf cutter and adjustable supporting means for said kerf cutter for positioning the latter wholly outside the trackway to cut a horizontal kerf at the level of the mine bottom outside and below the level of the mine trackway, or positioning said kerf cutter to cut a vertical kerf midway between the track rails, or a horizontal kerf at the level of the mine roof, and motor operated devices for driving the truck wheels to propel the apparatus bodily along the mine trackway to effect sumping and withdrawal movements of said kerf cutter.

53. In a mining apparatus, a wheeled truck adapted to run along a mine trackway, a motor on said truck fixed with respect thereto as to movement about a vertical axis, kerf cutting mechanism on said truck and driven by said motor including a pivoted kerf cutter, adjustable supporting means for said kerf cutter for positioning the latter wholly outside the trackway to cut a horizontal kerf at the level of the mine bottom outside and below the level of the mine trackway, or for positioning said kerf cutter to cut a vertical kerf midway between the track rails, or a horizontal kerf at the level of the mine roof, motor operated devices for adjusting said kerf cutter into aforesaid positions, and motor operated devices for driving the truck wheels to propel the apparatus bodily along the mine trackway to effect sumping and withdrawal movements of said kerf cutter.

54. In a mining apparatus, a portable base, a horizontal turntable mounted on said base for rotation relative thereto about a vertical axis, an arm structure pivotally mounted on said turntable adjacent the forward edge of the latter to swing in a vertical direction in a diametric plane relative thereto about a horizontal axis extending transversely of said arm structure, said arm structure extending in advance of said base, a kerf cutter pivotally mounted on the outer extremity of said arm structure to swing horizontally relative thereto to cut a horizontal kerf, and

means for swinging said arm structure in aforesaid vertical direction relative to said turntable to position the kerf cutter into parallel horizontal planes above and below the planes of said turntable.

55. In a mining apparatus, a portable base, a horizontal turntable mounted on said base for rotation relative thereto about a vertical axis, an arm structure pivotally mounted on said turntable to swing in a vertical direction relative thereto about a horizontal axis extending transversely of the arm structure, a kerf cutter pivotally mounted on the outer extremity of said arm structure to swing horizontally relatively thereto to cut a horizontal kerf, and means for automatically maintaining said kerf cutter parallel to a horizontal plane during vertical swinging of said arm structure about its axis relative to said turntable, said arm structure swinging in a plane diametric of said turntable.

56. In a mining apparatus, a portable base, a horizontal turntable mounted on said base for rotation relative thereto about a vertical axis, parallel links pivotally mounted on said turntable for swinging movement in a vertical direction relative thereto, a kerf cutter pivotally mounted on the outer extremities of said links for horizontal swinging movement relative thereto to cut a horizontal kerf, and means for swinging said links in aforesaid direction relative to said turntable to position the kerf cutter to cut horizontal kerfs above and below the level of said turntable.

57. In a mining apparatus, a wheeled truck adapted to travel along a mine trackway, adjustable kerf cutting mechanism on said truck including a kerf cutter, an adjustable supporting structure between said kerf cutter and said truck including a support turnable horizontally relative to said truck and an arm structure pivotally mounted on said support adjacent the forward edge of the latter to swing in a vertical direction in a diametric plane relative thereto about a horizontal axis extending transversely of the arm structure, said arm structure extending in advance of said truck and having on its outer extremity said kerf cutter pivotally mounted, and devices for adjusting said supporting structure to position said kerf cutter to cut horizontal kerfs above and below the level of said turntable including a horizontal kerf at the level of the mine floor outside and below the level of the mine trackway.

58. In a mining apparatus, a wheeled truck adapted to travel along a mine trackway, kerf cutting mechanism including a pivoted plane kerf cutter, an adjustable supporting structure for said kerf cutter including an adjustable arm structure swingable horizontally and vertically relative to said truck and on the outer extremity of which

said kerf cutter is pivotally mounted and adjustable to position said kerf cutter wholly outside the trackway to cut a kerf at the level of the mine floor outside and below the 5 level of the mine trackway, and means for maintaining said kerf cutter with its plane constantly parallel to a common plane during vertical swinging of said arm structure about its pivotal mounting relative to said 10 truck.

59. In a mining apparatus, a portable base, a horizontal turntable on said base, supporting means on said turntable, kerf cutting mechanism, and an adjustable supporting structure for said cutting mechanism plurally articulated to said supporting means for swinging adjustment relative to said turntable to position said kerf cutting mechanism, by movements during which 15 said cutting mechanism remains constantly parallel to a horizontal plane, into different parallel horizontal planes.

60. In a mining apparatus, a wheeled truck adapted to run along a mine track-way, a kerf cutter, parallel link members supporting said kerf cutter for movement into different parallel horizontal planes, means for adjusting said link members vertically relative to said truck to move the 25 kerf cutter into different parallel horizontal planes, and means for adjusting said link members horizontally relative to said truck to position said kerf cutter to cut a horizontal kerf at the level of the mine bottom outside and below the level of the mine 30 trackway.

61. In a mining apparatus, a portable base, a horizontal turntable mounted on said base, parallel links pivotally mounted on said turntable to swing in a vertical direction relative thereto about parallel horizontal axes, a frame to which the outer extremities of said links are pivotally connected about parallel horizontal axes, a kerf cutter pivotally mounted on said frame, and means for swinging said links in aforesaid vertical direction relative to said turntable to move the kerf cutter into different parallel horizontal planes.

62. In a mining apparatus, a portable base, a horizontal turntable on said base, an arm pivotally mounted on said turntable to swing in a vertical direction relative thereto about a horizontal axis transverse to said arm, a frame to which the outer extremity of said arm is pivotally connected about a parallel axis, a kerf cutter pivotally mounted on said frame, and means for swinging 50 said frame about its pivotal connection with said arm during vertical swinging of said arm about its axis relative to said turntable always to maintain the kerf cutter parallel to a common straight line.

63. In a mining apparatus, a portable base,

a horizontal turntable on said base, an arm pivotally mounted on said turntable to swing in a vertical direction relative thereto about a horizontal axis transverse to said arm, a frame to which the outer extremity of said arm is pivotally connected about a parallel axis, a kerf cutter pivotally mounted on said frame, and means for swinging said frame about its pivotal connection with said arm always to maintain the kerf cutter 70 parallel to a common straight line during swinging of said arm, said turntable and arm being adjustable relative to said base to position said kerf cutter to cut a horizontal kerf at the level of the mine bottom at one 75 side of said base.

64. In a mining apparatus, a portable base, a horizontal turntable on said base, an arm pivotally mounted on said turntable to swing in a vertical direction relative thereto about a horizontal axis transverse to said arm, a frame to which the outer extremity of said arm is pivotally connected about a parallel axis, a kerf cutter pivotally mounted on said frame, and means for swinging said 80 frame about its pivotal connection with said arm during swinging of said arm, said turntable and arm being adjustable relative to said base to position said kerf cutter to cut a horizontal kerf at the level of the mine bottom at one 85 side of said base.

65. In a mining apparatus, a portable base, a horizontal turntable on said base, an arm structure pivotally mounted on said turntable to swing in a vertical direction relative thereto, a horizontal plane kerf cutter pivotally mounted on the outer extremity of said arm structure, said turntable and arm structure being adjustable relative to said base to position said kerf cutter to cut a horizontal kerf at the level of the mine floor at one side 90 of said base, and means for maintaining said plane kerf cutter parallel to a horizontal 95 plane during vertical swinging of said arm structure about its pivotal mounting relative to said turntable.

66. In a mining apparatus, a portable base, a horizontal turntable mounted on said base for rotation relative thereto about a vertical axis, an arm structure pivotally mounted on said turntable to swing relative thereto, a plane kerf cutter pivotally mounted on the outer extremity of said arm structure to 100 swing relative thereto, and means for maintaining the plane of said kerf cutter always parallel to a common plane during swinging of said arm structure about its pivotal 105 mounting on said turntable.

67. In a mining apparatus, a portable base, a supporting structure mounted on said base to swing horizontally relative thereto about a vertical axis, an elongated kerf cutter carrying cutting elements along its length and 110

pivotedly mounted on said supporting structure to swing in a vertical direction relative thereto to cut a full depth vertical kerf in a vertical plane extending radially from the 5 supporting structure axis, and means for adjusting the kerf cutter to cut a relatively inclined kerf.

68. In a mining apparatus, a portable base, a supporting structure mounted on said base 10 for swinging movement horizontally relative thereto about a vertical axis and for rotative movement about a horizontal axis extending radially from said vertical axis, and a kerf cutter pivotedly mounted on said supporting structure to swing relative thereto and adjustable with said supporting structure relative to said base into positions to 15 cut a horizontal kerf at the level of the mine bottom at either side of said base and outside the path of movement of said base and to cut a vertical kerf lying in a vertical plane 20 extending radially from the vertical axis of said supporting structure and within which the horizontal axis of rotation of said supporting structure lies.

69. In a mining apparatus, a wheeled support adapted to run along a mine trackway, kerf cutting mechanism on said support including a pivoted kerf cutter, and adjustable 30 supporting means for said kerf cutter whereby the latter may be positioned wholly outside the trackway to cut a horizontal kerf at the level of the mine bottom outside and below the level of the mine trackway and 35 including a support rotatable about a horizontal axis to position said kerf cutter to cut a vertical kerf extending in the direction of the trackway and midway between the sides of the apparatus while the axis of said rotatable support extends longitudinally of and midway between the sides of the apparatus.

70. In a mining apparatus, a wheeled support adapted to run along a mine trackway, 45 kerf cutting mechanism on said support including a pivoted kerf cutter and adjustable supporting means for said kerf cutter whereby the latter may be positioned wholly outside the trackway to cut a horizontal kerf 50 at the level of the mine bottom outside and below the level of the mine trackway, or whereby said kerf cutter may be positioned to cut a vertical kerf extending in the direction of the trackway and midway between 55 the sides of the apparatus, and a motor on said support and relative to which said supporting means is adjustable for adjusting said kerf cutter into aforesaid positions.

71. In a mining apparatus, a wheeled support 60 adapted to run along a mine trackway, kerf cutting mechanism on said support including a pivoted kerf cutter, and adjustable supporting means for said kerf cutter for positioning the latter wholly outside the trackway to cut a horizontal kerf at the level

of the mine bottom outside and below the level of the mine trackway, or for positioning said kerf cutter to cut a horizontal kerf at the level of the mine roof, and including a support rotatable about a horizontal axis to position said kerf cutter to cut a vertical kerf extending parallel to the track rails and midway between the track rails while the axis of said rotatable support extends longitudinally of the apparatus and lies midway between the sides of the latter.

72. In a mining apparatus, a wheeled support adapted to run along a mine trackway, kerf cutting mechanism on said support including a pivoted kerf cutter and adjustable supporting means for said kerf cutter for positioning the latter to cut, with said kerf cutter wholly outside said trackway, a horizontal kerf at the level of the mine bottom outside and below the level of the mine trackway, to cut a vertical kerf extending parallel to the track rails and midway between the track rails or a horizontal kerf at the level of the mine roof, and a motor on said support and relative to which said supporting means is adjustable for adjusting said kerf cutter into aforesaid positions.

73. In a mining apparatus, a wheeled support adapted to run along a mine trackway, kerf cutting mechanism on said support including a pivoted kerf cutter, and adjustable supporting means for said kerf cutter for positioning the latter into different parallel horizontal planes between the mine bottom and the mine roof and including a support 95 rotatable about a horizontal axis to adjust said kerf cutter into vertical cutting positions between the ribs of the entry including a vertical cutting position midway between the track rails and extending parallel 100 with the latter while the axis of said rotatable support extends longitudinally of and midway between the sides of the apparatus, said adjustable supporting means also including means for positioning the kerf cutter wholly outside the trackway to cut a horizontal kerf at the level of the mine bottom outside and below the level of the mine trackway.

74. In a mining apparatus, a portable base, a horizontal turntable on said base, kerf cutting mechanism supported by said turntable including a cutter head rotatable about an axis extending radially from the axial line of the turntable, a pivoted kerf cutter supported on said head, and adjustable supporting means for said kerf cutter for moving the latter through a series of parallel cutting positions toward and from the axial line of said head and into said axial line.

75. In a mining apparatus, a portable base, a horizontal turntable on said base, and kerf cutting mechanism supported by said turntable including a rotatable neck frame disposed on a horizontal axis and a pivoted kerf

- cutter supported by said neck frame adjustable through a series of parallel cutting positions toward and from the axial line of said neck frame and into said axial line.
- 5 76. In a mining apparatus, a portable base, a horizontal turntable on said base, motor operated devices for rotating said turntable, a cutter head mounted on said turntable for rotation about an axis extending radially from the axial line of the turntable, motor operated devices for rotating said cutter head about its axis, and a pivoted cutter bar supported by said head and adjustable through a series of parallel cutting positions relative thereto toward and from the axial line of said head and into said axial line.
- 10 77. In a mining apparatus, a wheeled support adapted to run along a mine trackway, kerf cutting mechanism mounted on said support and including a pivoted kerf cutter, and adjustable supporting means for said kerf cutter for adjusting the latter to make a horizontal cut, with said kerf cutter wholly outside the trackway, at the level of the mine bottom outside and below the level of the mine trackway and including a support rotatable about a horizontal axis to position said kerf cutter to make a vertical cut extending in the direction of the trackway midway between the sides of the apparatus while the axis of said rotatable support extends longitudinally of the apparatus, and motor operated devices for adjusting said kerf cutter into aforesaid positions.
- 15 78. In a mining apparatus, a portable base, a frame mounted on said base for rotation about a vertical axis, a rotary supporting body mounted on said frame for rotation about a horizontal axis, an elongated kerf cutter, and means intervening said supporting body and said kerf cutter for carrying the latter for orbital movement around the axial line of said rotary supporting body and through a series of parallel cutting positions toward and from and into said axial line and to swing in planes parallel to said axial line.
- 20 79. In a mining apparatus, a portable base, a frame mounted on said base for rotation about a vertical axis, a rotary body mounted on said frame for rotation about a horizontal axis, an elongated kerf cutter, and means intervening said body and said kerf cutter for carrying the kerf cutter parallel to the axial line of said body for orbital movement around said line and through a series of parallel cutting positions from and toward and into said line and for swinging said kerf cutter in a plane parallel to said axial line.
- 25 80. In a mining apparatus, a portable base, a horizontal turntable on said base, supporting means having a neck seated rotatably in a bearing on said turntable, an elongated cutting mechanism hinged to said supporting means to permit movement of said cutting mechanism bodily toward and from the axial line of said neck while remaining parallel to said axial line, a motor mounted on said base and relative to which said turntable and supporting means are rotatable, and transmission means driven by said motor and extending through said neck for actuating said cutting mechanism.
- 30 81. In a mining apparatus, a portable base, a support mounted on said base for adjustment horizontally relative thereto about a vertical axis and including supporting means having a neck seated rotatably in a bearing, an elongated kerf cutting mechanism hinged to said supporting means for moving said cutting mechanism toward and from the axial line of said neck while said cutting mechanism remains parallel to said axial line, a motor mounted on said base and relative to which said support and supporting means are rotatable, and transmission means driven by said motor and including a neck shaft extending through said neck and arranged in operative relation with the cutting mechanism for actuating said cutting mechanism.
- 35 82. In a mining apparatus, a wheeled support adapted to run along a mine trackway, kerf cutting mechanism mounted on said support and including a neck frame rotatable about a horizontal axis and a pivoted kerf cutter adjustably mounted on said neck frame for movement, while said kerf cutter remains continuously parallel to the axial line of the neck, toward and from and into the axial line of said neck, mechanism for rotating said neck frame to move said kerf cutter orbitally about the neck axis, mechanism for bodily adjusting said kerf cutting mechanism horizontally relative to said support to position said kerf cutter wholly outside the trackway and in low planes, to cut a horizontal kerf at the level of the mine bottom outside and below the level of the mine trackway, and a motor on said support and relative to which said neck frame is rotatable for driving said kerf cutting mechanism.
- 40 In testimony whereof I affix my signature.
- CHARLES F. OSGOOD.
